UNITED STATES PATENT OFFICE.

MAY CATHERINE BOWEN, OF CANON CITY, COLORADO.

PROTECTIVE DEVICE FOR INFANTS' HANDS.

1,260,865.

Specification of Letters Patent. Patented Mar. 26, 1918.

Application filed December 1, 1917. Serial No. 204,860.

To all whom it may concern:

Be it known that I, MAY CATHERINE BOWEN, a citizen of the United States, residing at Canon City, in the county of Fremont and State of Colorado, have invented 5 new and useful Improvements in Protective Devices for Infants' Hands, of which the following is a specification.

This invention relates to protecting devices for the hands of infants, and the primary object of the same is to provide a simple and effective means that may be readily applied over the hands of infants to prevent all danger of breaking or dislocating the 10 fingers or thumbs or causing distress by having the fingers or thumbs of an infant catch in the cloth of the sleeves of a garment. An infant's fingers naturally tend to spread out and stiffen when its hand or arm is held in 15 a position to apply the sleeve of a garment thereto. Consequently, when the arm of an infant is raised for the purpose of putting it into a sleeve, the fingers of the hand invariably spread out and stiffen and cause 20 them to catch in the cloth and, as a result, the infant is distressed and, moreover, the fingers are liable to become permanently injured and very particular and careful attention is required on the part of an attendant 25 to avoid injuring the infant in this manner.

With this and other objects and advantages in view, the invention consists in the construction and arrangement of the several 30 parts which will be more fully hereinafter described and claimed.

In the drawing:

Figure 1 is a perspective view of the improved protecting device or cone.

Fig. 2 is a rear end elevation of the same.

Fig. 3 is a central longitudinal vertical section.

The numeral 5 designates a cone-like body or member preferably formed of celluloid or 45 other analogous material adapted for the purpose and which is smooth and rigid enough to effect the function for which the device has been devised. The body or member 5 will be of such proportions as to permit 50 the insertion of the hand of an infant thereinto without cramping or in anywise squeezing or injuring the hand or fingers of the latter. Secured to the rear open end 6 of the body or member 5 is a partial closure 55 7 of silk or other similar material which is fastened to the edge of the open end 6 of the

body or member 5, as at 8, by any suitable means, for instance, by thread stitches, as shown, though the exact manner of securing this partial closure to the open end of the 60 body or member 5 is not essential as various means could be adopted to permanently retain the partial closure in applied position. The partial closure or the silk or other material extends straight toward the center of 65 the body or member 5 and is flat and formed with folds or plaits converging toward the center of the open end 6 of the said body or member 5 and providing an excess of material which is normally held taut by an elastic 70 or rubber band 9 inclosed within a hem 10 or other analogous device which is formed either by turning over the material of the partial closure 7 around the center, or, it may be an independent structure and attached to the closure to provide an elastically 75 confined central opening 11 which is normally of less diameter than that of the wrist of an infant or baby.

In the use of the improved device, the 80 hand of the infant is inserted through the opening 11 and the elastic or rubber band 9 is thereby stretched and at the same time loosens the partial closure 7 as will be readily understood, and when the hand has been 85 fully inserted within the cone-like body or member 5, the rubber band 9 will tend to resume its normal position and bind the wrist of the hand inclosed with sufficient stress to prevent the accidental detachment 90 of the cone which serves as a guard but will not in anywise inconvenience or irritate the infant. There will be, of course, a protective device of the character specified applied to each hand, and by this means the fingers 95 will be inclosed, yet the infant will have free use of the fingers or can move the same within the body or member 5. By means of the protective device, the hands and arms of the infant may be readily inserted 100 through the sleeve of a garment in dressing an infant and the protective device may be very easily pushed through the sleeve of the garment, and after the garment is fully applied the protective devices may be readily 105 removed from the hands. It will be understood that the dimensions of the improved protective device or cone may be modified, but it is proposed to make them of such uniform size that they will receive 110 a large or a small hand and be also of such dimensions generally as to be readily in-

sertible through a sleeve or other garment opening.

What is claimed is:

1. A protective device for the hands of infants, consisting of a cone-like body with a straight open end at the maximum diametric portion of said body and having an inwardly extending straight partial closure over said open end provided with a central 5 elastically confined opening of normally less dimension than the wrist of an infant to yieldingly bind on the wrist and hold the device in applied position.
2. A protective device for the hands of infants, consisting of a cone-like practically rigid body with an opening at one end at the maximum diametric portion of said body and having a dimension larger than the maximum dimensions of an infant's hand 15 and wrist, the opposite end of the body being closed, and an inwardly extending flat partial closure disposed straight over the 20

portion of said open end covered thereby and provided with a central elastically confined opening of less dimension than the hand 25 and wrist of an infant.

3. A protective device for the hands of infants, consisting of a body closed at one end and the opposite end formed with an opening larger than the maximum dimensions of the hand and wrist of an infant, and a flat normally taut partial closure over the said opening of the body extending inwardly from the periphery of the latter to a central elastically confined opening of less 30 dimension than the dimensions of the hand and wrist of an infant.

In testimony whereof I have hereunto set my hand in presence of two subscribing witnesses,

MAY CATHERINE BOWEN.
